UNITED STATES PATENT OFFICE.

GEORGE D. REED, OF SPRINGFIELD, VERMONT, ASSIGNOR TO HIMSELF,
JULIUS E. GRAVES, AND WILLARD BAILEY, OF SAME PLACE.

IMPROVEMENT IN GUITARS.

Specification forming part of Letters Patent No. **150,355**, dated April 23, 1874; application filed
January 7, 1874.

To all whom it may concern:

Be it known that I, GEORGE D. REED, of Springfield, in the county of Windsor and State of Vermont, have invented a new and Improved Guitar; and that the following is a full, clear, and exact description of the same, reference being had to the accompanying drawings, and to the letters of reference marked thereon, making a part of this specification.

This invention is in the nature of an improvement in guitars; and the invention consists in a guitar constructed with its back and sides formed from thin sheet metal, and with its front or sounding-board formed of wood, as hereinafter described.

In the accompanying drawings, Figure 1 is a front elevation of my guitar; and Fig. 2, a cross-section of the same, taken in line *x x*.

Similar letters of reference indicate like parts in the two figures.

The back *A* is formed of the required size and shape from thin sheet metal, and the sides

B are made from one continuous strip of metal, bent to the requisite form, and soldered or otherwise secured to the back *A*. To the upper edges of the sides *B* is secured, in any desirable manner, a wooden face or sounding-board, *C*, provided with the usual orifice *g*, for the emission of sound. To the sounding-board is affixed the ordinary string-cleat *a* and neck *b*, the neck being provided with the usual frets and head *e* for the pegs *f*.

A guitar constructed as described above will be found strong, sonorous, and comparatively inexpensive.

Having thus described my invention, what I claim as new, and desire to secure by Letters Patent, is—

A guitar constructed with metallic back and sides, in combination with a wooden sounding-board, substantially as described.

GEORGE D. REED.
